UNITED STATES PATENT OFFICE.

MAURICE GINSBURG, OF PLUMSTEAD, ENGLAND.

DESIGN FOR A POCKET-LIGHTER.

54,314.

Specification for Design.

Patented Dec. 23, 1919.

Application filed July 11, 1919. Serial No. 310,278. Term of patent 7 years.

To all whom it may concern:

Be it known that I, MAURICE GINSBURG, a Canadian subject, residing at Plumstead, county of Kent, England, have invented a new, original, and ornamental Design for a Pocket-Lighter, of which the following is a specification, reference being had to the accompanying drawing, forming part thereof.

The figure is a side elevation of a pocket lighter showing my new design.

The features of the design consist of a body member 1, composed of an empty rifle cartridge of the type of a U. S. A. magazine rifle cartridge, having a rounded knob 2, secured into the cap end of the body or cartridge, and a cover 3 in the shape of a bullet at its opposite or mouth end. A collar

4 engages over the mouth end of the cartridge and secures a flint holder 5 to the cartridge. The flint holder extends parallel with the cartridge and carries an igniter, which at its upper end is adjacent the cover 3.

I claim:

A new and ornamental design for pocket lighter, as shown and described.

In witness whereof, I hereunto subscribe my name, as attested by the two subscribing witnesses.

MAURICE GINSBURG.

Witnesses:

EDWARD C. HARRIS,
HAROLD MAUSER.
